UNITED STATES PATENT OFFICE.

JAMES A. COHOON, JR., OF CREVE COEUR, MISSOURI, ASSIGNOR TO AULOGO MOTOR CAP COMPANY, OF ST. LOUIS, MISSOURI, A CORPORATION OF MISSOURI.

MOTOR-CAP.

1,134,515.

Specification of Letters Patent.

Patented Apr. 6, 1915.

Application filed December 30, 1913. Serial No. 809,502.

To all whom it may concern:

Be it known that I, JAMES A. COHOON, Jr., citizen of the United States, residing at Creve Coeur, in the county of St. Louis and State of Missouri, have invented certain new and useful Improvements in Motor-Caps, of which the following is a specification.

My invention relates to new and useful improvements in head coverings and more particularly to head coverings of the type commonly called caps, the object of my invention being the provision of a convertible cap so constructed as in ordinary use to leave the face of the wearer exposed but capable of being pulled down or extended to provide a mask or covering for the wearer's face.

A further object of my invention is to provide a cap of the above described character in which the lower edge portion of the crown is expandable in order that such portion may fit snugly either about the upper portion of the wearer's head or about the head and face of the wearer.

A further object of my invention is to provide a cap of the type in which the crown is normally drawn forward to rest upon the upper portion of the vizor with an insert of transparent material in that portion of the crown normally resting upon the vizor, which, when the cap is drawn down over the wearer's face, will extend in front of the eyes.

In this connection, a still further object of my invention is to so construct the cap that it will engage snugly across the wearer's face and over the bridge of the nose, thereby shutting out any dust or dirt.

With these and other objects in view, my invention will be more fully described, illustrated in the accompanying drawing, and then specifically pointed out in the claims which are attached to and form a part of this application.

In the drawing:—Figure 1 is a perspective view of a cap constructed in accordance with my invention, showing the same employed to shield the wearer's face; Fig. 2 is a longitudinal sectional view taken through the cap in the position shown in Fig. 1, bringing out the manner in which it fits about the wearer's head; Fig. 3 is a perspective view, showing the cap with the vizor in raised or normal position; Fig. 4

is a fragmentary sectional view taken through the lower back portion of the crown, showing an attached elastic member employed to insure snug fitting of the cap in either position.

Corresponding and like parts are referred to in the following description and indicated in all the views of the drawing by the same reference characters.

My improved cap is primarily intended as an outing cap for motorists, whereby the necessity of wearing goggles or other protective articles or coverings for the eyes will be avoided, the cap being so constructed as to protect the wearer in a much more efficient manner than any of the ordinary forms of goggles now on the market. Goggles, as a rule, leave the greater part of the face exposed to wind and dust, or, if constructed to cover the entire face, are extremely uncomfortable because of the fact that they fit so closely about the face as to interfere with the breathing and talking of the wearer. Furthermore, they are an added article of apparel and as such are liable to become lost or misplaced. My improved cap is so constructed as to be capable of protecting the entire face of the wearer from wind and dust when such protection is required.

More specifically my improved cap is of that type commonly known as golf or outing caps including a flexible crown or body portion 10 of cloth or other soft material and a vizor or eye shade 11 formed either of the same material as the body of the cap or of other suitable material, the vizor, as a rule, being stiffened or reinforced in order that it may keep its shape. The crown portion of the cap is flared intermediate its height in order that, under ordinary circumstances, the forward lower part of the crown may be pulled ahead to rest upon the upper face of the vizor as shown in Fig. 3, the crown being maintained in this position by means of any suitable fastening device such as a snap fastener including the co-acting parts 12 and 13. Caps of the above described type are in common use and any further description of the construction of the cap proper is therefore unnecessary.

Such a cap is worn with the lower part of the crown fitting snugly about the head and forehead of the wearer and my improved cap is adapted to be worn either in

that manner or with the lower part of the crown fitting about the head and across the cheeks and nose of the wearer as shown in Fig. 2. In order that the cap, when drawn down in this manner, may not bind too tightly about the head and when worn in the manner shown in Fig. 3 may not fit too loosely, the lower edge portion of the crown is made larger or fuller than usual and 10 gathered at the rear as shown at 14, a strip of elastic material 15 being stitched or otherwise secured along the inner rear edge of the cap in order to normally hold the cap in the proper size to be worn in the manner 15 shown in Fig. 3. This elastic material may, however, be readily expanded or stretched in order to permit the gathered portion of the cap to be extended so that the cap may be worn as shown in Fig. 2. It will of course be clear than when worn in either manner, the cap will fit snugly about the wearer's head and be held against casual displacement therefrom.

The lower forward portion of the crown 25 of the cap is cut-away as at 16 to provide a sight opening closed by a sheet 17 of any suitable transparent material, such as celluloid, isinglass, glass or the like. This transparent sheet is preferably secured over the 30 opening interiorly of the cap by a row of stitching or other suitable fastening means and the opening in the crown is so proportioned that the transparent sheet will extend across both eyes of the wearer when 35 the cap is drawn down over the face. At the same time, when the cap is worn upon the upper part of the head with the forward portion of the crown pulled down over the vizor, the sheet of transparent material rests upon the upper face of the vizor 40 and is covered by the upper portion of the crown of the cap, being thereby hidden from sight and protected from injury.

The lower intermediate portion of this 45 transparent sheet 17 is cut-away as shown at 19 to fit across the bridge of the wearer's nose and the vizor of the cap is also cut-away at 20 to fit about the nose of the wearer. A shield 21 of soft flexible material is secured by its edges to the adjacent edges of the transparent sheet and vizor to cover that portion of the wearer's nose which would otherwise be exposed, due to the cutting away of such parts at 19 and 20.

50 Ordinarily the cap is worn in the manner shown in Fig. 3, but if, for any reason, the wearer wishes to protect his face from dust, wind or rain, the members 12 13 of the snap fastener are separated and the vizor pulled down across the face to the position shown in Figs. 1 and 2. When so worn the forward portion of the crown, including the transparent sheet 17, together with the vizor, cover and protect the entire face of the 55 wearer, although the vizor, as shown, sets

away from the face in such a manner as to in no way interfere with the breathing of the wearer or to hinder his talking. The cap when worn in this manner is ordinarily pulled down in such a manner as to cover 70 the wearer's ears as shown in Fig. 1, although it may be worn in the slightly different manner shown in Fig. 2 to leave the ears exposed.

The cap does not bind about the wearer's 75 nose, due to the expansion of the elastic strip 15 and the cutting away of the vizor, the engagement of the cap being about the head and across the wearer's cheeks. By properly proportioning the size of the cap and the 80 strength of the elastic band, the cap may be made to fit the head snugly in either position without undue pressure. The transparent sheet or shield closing the sight opening in the crown of the cap may be of clear transparent material or may be tinted or colored to protect the wearer's eyes from glare of the sun. If desired, the cap may be provided at each side of the opening 16 with a series of perforations 22, preferably in the 85 form of eyelet holes for purposes of ventilation.

From the foregoing description, taken in connection with the drawing, it will be apparent that I have provided an improved 90 form of cap construction and one which, while in ordinary use is as neat and finished in appearance as caps now commonly on the market, is capable of being readily converted into a combined cap and face shield. The 95 cap may be readily changed from one position to the other while still upon the head, but one hand being necessary for this operation. Such a cap can be made at slight 100 increase in cost over the manufacturing cost 105 of caps now commonly in use and will therefore be much cheaper than goggles besides possessing other numerous advantages over goggles, some of which have been pointed out.

110 It will of course be understood that I do not wish in any way to limit myself to the specific details of construction illustrated in the drawing and described in the specification, as various minor changes, within the 115 scope of the appended claims, may at any time be made without in the slightest degree departing from the spirit of my invention.

Having thus described the invention, what is claimed as new is:

120 1. A convertible cap including a crown and vizor, the forward portion of the crown adjacent the vizor having an opening, a transparent member covering the opening, portions of the vizor and transparent member being cut-away, and a covering of soft material inserted in the cut-away portions of the transparent member and vizor.

125 2. A convertible cap including a crown and vizor, the crown being expandable where-

by the cap may be drawn down over the wearer's face, the vizor being cut-away to fit about the nose of the wearer when the cap is so worn, a nose covering inserted in the vizor, the crown being provided with a sight opening, and a transparent member covering the sight opening.

3. A convertible cap including a crown having an opening in its lower forward portion and a series of ventilating openings at either side of the first opening, and a transparent member covering the first opening.

4. A convertible cap including a crown and vizor, the crown being expansible, whereby the cap may be drawn down over the wearer's face, the vizor being cut-away to fit about the nose of the wearer when the cap is so worn, and a nose covering inserted in the vizor.

20 5. A convertible cap including a crown

and vizor, the forward portion of the crown adjacent the vizor having an opening, a transparent member covering the opening, a portion of the vizor being cut-away, and a covering of soft material inserted in the cut-away portion of the vizor.

6. A convertible cap including a crown and vizor, the crown being expansible, whereby the cap may be drawn down over the wearer's face, the lower forward portion of the crown being provided with an opening, a transparent member covering the opening, and means for admitting air through the forward portion of the cap.

In testimony whereof I affix my signature 35 in presence of two witnesses.
